UNITED STATES PATENT OFFICE.

FRED RIEBEL, JR., OF RACINE, WISCONSIN, ASSIGNOR TO HAMILTON-BEACH MFG. CO., OF RACINE, WISCONSIN, A CORPORATION OF WISCONSIN.

SPINDLE MOUNTING.

Application filed November 29, 1921. Serial No. 518,512.

To all whom it may concern:

Be it known that I, FRED RIEBEL, Jr., a citizen of the United States, residing at Racine, county of Racine, and State of Wisconsin, have invented certain new and useful Improvements in Spindle Mountings, fully described and represented in the following specification and the accompanying drawings, forming a part of the same.

This invention relates to spindle mountings and more particularly to mountings for the brush spindles of vacuum cleaners.

It is an object of the invention to provide a simple and effective self-oiler for spindle 15 journals.

It is a further object of the invention to provide a mounting for vacuum cleaner brush spindles that permits easy adjustment of the position of the spindle to compensate for wear of the brush bristles.

With these general objects in view the invention consists in the features, combinations, details of construction and arrangements of parts which will first be described 25 in connection with the accompanying drawing and then more particularly pointed out.

In the drawing,

Fig. 1 is a view of a vacuum cleaner constructed in accordance with the invention, 30 with parts in said elevation and parts in vertical section;

Fig. 2 in a section view (enlarged) taken on the line 2 of Fig. 1;

Fig. 3 is an enlarged view showing in vertical section one end of the spindle and its mounting; and

Fig. 4 is a sectional view taken on the line 4 of Fig. 3.

Referring to the drawing, the invention 40 in its entirety includes in combination with a spindle and its journal, a journal box having a portion serving as a bearing and a portion for holding a lubricating element in contact with the journal and means tending 45 to draw the journal into the bearing portion of the journal box. The spindle illustrated as an example is the brush spindle of a vacuum cleaner. Although capable of various constructions, in the present embodiment 50 there is provided a brush spindle 11 having reduced end journals 12 formed by a rod 13 extending through the spindle. The spindle 11 has a plurality of brush bristles 14 arranged thereon in any suitable manner.

The journal box here shown as an example

comprises a casing 15 open at its inner end and closed at its outer end, as appears in Fig. 3. The casing 15 is trough shaped (Fig. 4), the apex of the trough constituting a bearing portion 16 for the spindle journal 60 12. The flaring portion 17 of the journal box provides a chamber for holding a lubricating element such as oil-soaked packing 18. It will be understood that each end of the spindle has a journal and journal box, 65 these elements being duplicates of each other.

While the means for drawing the journals into the bearings may vary, this may be accomplished conveniently by the elements 70 that drive the spindle. In the exemplification illustrated, the spindle is rotated by means of a belt 19 formed of rubber or other suitable material. This belt runs over a spindle pulley 20 and over a crown pulley 75 21 on a driven shaft 22. As shown, this shaft is an extension from a fan shaft driven by a motor contained in the motor casing 23, fan shaft and motor not being shown.

The journal boxes are so mounted that the 80 apex of the trough points upwardly, a suitable mounting being hereinafter described. The pull of the elastic belt on the spindle tends to draw the journals 12 into the bearings 16 formed by the apex of the journal boxes. With the construction described the journals have a positive bearing and at the same time they are rotated in contact with the oil-soaked packing 18 and are thus self-oiling.

To protect the journal boxes from dirt and the like, caps are provided. As here illustrated as an example, integral with the journal box 15 is a flange 24, turned inwardly, as appears in Fig. 3, to form a cylindrical skirt 95 25 that slips over the end of the spindle.

The invention in its entirety includes, in combination with a nozzle having a suction mouth, means for mounting the brush spindle at varying distances above the plane of 100 the mouth, thereby to adjust the spindle to compensate for wear of the bristles. This may be accomplished, for example, by providing for each end of the spindle, an angularly movable bracket having differentially 105 arranged pockets for receiving spindle-end supporting members. Although capable of various constructions, in the embodiment here illustrated as an example, in front of the motor casing 23 is a fan casing 26 which 110

communicates with a nozzle 27 having a suction mouth 28. Motor casing, fan casing and nozzle constitute the body of the cleaner which is supported on running wheels 29 and moved about by a handle 30.

The brush spindle is so mounted that the bristles extend through the suction mouth to engage the surface to be cleaned. In the present embodiment, the spindle-end supports referred to are the journal boxes 15. The pockets for the journal boxes are U-shaped notches 31 formed in the periphery of a circular bracket or plate 32. These notches are of different depth and the plate 32 is angularly movable to bring any desired notch into position to receive the journal box. As here shown, the plates or brackets 32 are mounted on the inside of the end walls of the nozzle by axial bolts 33. Pins 34 are threaded into the nozzle wall to engage notches not in use and prevent the brackets 32 from turning. As appears in Fig. 4, the journal boxes seat in those notches which open downwardly, the spindle being held in place up in these notches, in the present embodiment, by the pull of the belt 19.

When the brush is new, the brackets 32 are arranged so that the deepest notch is in position to receive the spindle end supports, in this case the journal boxes. As the brush bristles become worn and consequently shorter, the spindle may be positioned closer to the suction mouth. To this end, the belt 19 is removed, a cap 35 in the front of the nozzle providing access to the belt. Removal of the belt permits the spindle with the journal boxes to be removed from the brackets. The brackets are then rotated one quarter turn to place the next shorter notch in bottom position. The spindle with its journal boxes and the belt being repaced, the spindle is now closer to the suction mouth so the worn bristles can properly function.

45 What is claimed is:

1. In combination, a spindle having a journal, a journal box formed to provide an open-sided bearing for the journal and having a chamber for holding a lubricating element in contact with the journal, and means tending to draw the journal into the bearing portion of the journal box.

2. In combination, a spindle having a journal, a journal box having a portion serv-

ing as a bearing for the journal and a portion for holding a lubricating element in contact with the journal, and driving means for the spindle, the parts being so arranged that the driving means tends to draw the journal into the bearing portion of the journal box.

3. In a vacuum cleaner, in combination, a brush spindle having a journal, a journal box having a portion serving as a bearing for the journal and a portion for holding a lubricating element, a driven shaft, and a resilient belt for driving the spindle from said shaft, the pull of the belt on the spindle tending to draw the journal into said bearing portion.

4. In a vacuum cleaner, in combination with a nozzle having a suction mouth, a brush spindle, a plurality of brush bristles thereon, an angularly movable bracket for each end of the spindle, carried by the nozzle and having a plurality of differentially arranged pockets, and spindle-end supports insertable in said pockets, whereby the position of the brush above the plane of the suction mouth can be adjusted to compensate for wear of the bristles.

5. In a vacuum cleaner, in combination with a nozzle having a suction mouth, a brush spindle, a plurality of brush bristles thereon, journals on the spindle, journal boxes, and an angularly movable bracket for each end of the spindle carried by the nozzle and having a plurality of notches for the reception of said journal boxes, said notches being of different depths, whereby the spindle may be mounted at varying distances above the plane of the suction mouth, to compensate for wear of the bristles.

6. In a vacuum cleaner, in combination with a nozzle having a suction mouth, a brush spindle, a plurality of brush bristles thereon, an angularly movable bracket, for each end of the spindle, carried by the nozzle and having a plurality of open-ended notches of different depths, spindle-end supports insertable in said pockets, a drive shaft, and a resilient belt for driving the spindle from said shaft and for pulling the supports into said notches.

In testimony whereof, I have hereunto set my hand.

FRED RIEBEL, JR.
